UNITED STATES PATENT OFFICE

GEORGE M. COX, OF MANSFIELD, OHIO.

TWO-WHEELED VEHICLE.

SPECIFICATION forming part of Letters Patent No. 451,029, dated April 28, 1891.

Application filed August 23, 1890. Serial No. 362,851. (No model.)

To all whom it may concern:

Be it known that I, GEORGE M. COX, a citizen of the United States, residing at Mansfield, in the county of Richland and State of Ohio, have invented certain new and useful Improvements in Two-Wheeled Vehicles; and I do declare the following to be a full, clear, and exact description of the invention, such as will enable others skilled in the art 5 to which it appertains to make and use the same.

My invention relates to improvements in two-wheeled vehicles; and the objects of my invention are, first, to provide a means to obviate all jerking movement caused by the motion of the horse, which is termed "horse motion;" second, to provide a two-wheeled vehicle that will be as easy in motion as a four-wheeled vehicle; third, to obviate the 15 necessity of using a suspension-strap for the front of body, at the same time to be durable and cheap in construction. I attain these objects by the mechanism illustrated in the accompanying drawings, in which—

20 Figure 1 is a vertical side view of a two-wheeled vehicle, showing the general construction of my invention. Fig. 2 is an end view of same, showing the construction of half-spring and flexible connections. Fig. 3 25 is an enlarged view of one of the flexible connections, showing its general construction. Fig. 4 is a front view of same.

Similar letters refer to similar parts throughout the several views.

30 In the accompanying drawings A indicates a single axle, upon which is mounted the elliptical springs B and B'. Said springs are secured to the axle by means of clips.

Secured upon the upper arch of the elliptic 35 springs B and B' are the standards C and C'. The said standards are secured in position upon the springs B by clips D. The standards are constructed with a hole in the upper end to receive the clevis E, which is secured rigid in the standard C, or may form part of said standard.

F indicates a half-elliptic spring, which is secured to the under side of the body G by any suitable mechanism, and centrally with 40 the axle. This spring is constructed with a slot in each end to receive the knuckle-joint

H, forming part of the connection between the springs B and half-spring F. The standard C is also provided with the knuckle-joint H'. I and I' indicate metallic plates or bars, 55 which are pivoted to the knuckle-joints H and H' by the bolts or rivets J. These connections are to allow the body to reciprocate in any direction. K also indicates a universal connection, which is constructed 60 similar to the connection described. These connections, however, at their upper ends are connected to the side springs by a clevis, which forms the bolt connecting the two halves of the side springs. The upper end of 65 the connection K is pivoted within the clevis L, the lower end being pivoted to the plate M' secured to the under side of the body, as shown in Figs 1 and 2. Figs. 3 and 4 show the construction of the connections. It will 70 be readily seen that each of the connections having knuckle-joints at the top and bottom, and the upper ends being attached to the side springs, the lower ends connected to the half-spring and the body, allows a reciprocatory movement to the body and obviating 75 all jerk motion common in all two-wheeled vehicles.

Two half-springs may be used in the place of the one shown under the seat, one on each 80 side of the vertical center of the axle, with double connections, which would obviate the necessity of using a metallic connection in the front. A flexible connection may be used there.

Having fully described my invention, what I claim as new, and desire to secure by Letters Patent, is—

1. In a two-wheeled vehicle, the combination of the axle, the springs mounted thereon, 90 the body, the half-spring having the pintles, the knuckles on the pintles forming joints, the knuckle-joints connected to the springs, and the bars or plates connected to the joints, substantially as described.

2. In a two-wheeled vehicle, the combination, with the axle, shafts, and body, of a brace-rod connecting the tops of the side springs, a half spring or springs secured upon the under side of the body, universal connections from the half-springs to the center of the side springs, and universal connections from

the front end of the side springs to the body, arranged as shown, and for the purpose specified.

3. In a two-wheeled vehicle, the combination of the axle, springs, and body, the half-spring secured to the body, the connections between the half-spring and elliptical springs, and the connection between the front end of

the body and front end of the springs, substantially as shown. 10

In testimony whereof I affix my signature in the presence of two witnesses.

GEORGE M. COX.
